UNITED STATES PATENT OFFICE.

DANIEL M. COX, OF MOULTON, IOWA.

COMBINATION HAY AND STOCK RACK.

SPECIFICATION forming part of Letters Patent No. 662,766, dated November 27, 1900.

Application filed May 10, 1900. Serial No. 16,246. (No model.)

To all whom it may concern:

Be it known that I, DANIEL M. COX, of the city of Moulton, in the county of Appanoose and State of Iowa, have invented a new and Improved Hay and Stock Rack, of which the following is a description.

This invention relates to new and useful improvements in combination hay and stock racks.

10 The invention is clearly illustrated in the accompanying drawings, in which—

Figure 1 is a perspective view of the apparatus adjusted as a hay-rack. Fig. 2 is a side elevation of my invention adjusted for use 15 as a wagon-box. Fig. 3 is a detail view of an end-gate to the box. Fig. 4 is an edge view of a rack-wing. Fig. 5 is a detail, and Fig. 6 is a detail of the front end of the box.

Reference now being had to the details of 20 the drawings by letter, A A designate the longitudinal base-pieces of the rack, which are connected together by suitable cross-pieces M, which are recessed at their ends to receive the ends of said pieces A. The wings 25 of the rack comprise the strips E, to the inner ends of which pins E' are secured, the latter being designed to engage the apertures C in the longitudinal pieces A. To said cross-strips E are secured the boards D. Where 30 the strips E rest upon the upper edges of pieces A, the latter are notched, as at A', as are also the under faces of said pieces F, as at e, Fig. 4.

To the end piece M is fastened a socket- 35 plate N, which receives the lower tapering end of the standard P, which may be held in place by means of a pin O, as shown in Fig. 1. To the rear cross-piece of the rack is also secured a standard P', which standards are

apertured, as at Q, to receive the ends of the 40 binding-bars J, the inner ends of which are held by the straps K, thus allowing the two bars to slide longitudinally in contact with each other. These bars may be held in either of the sets of apertures Q, as may be desired. 45

When the wings W are adjusted as a box, the lower ends of the cross-pieces W' may be placed in the sockets R and held in vertical positions. The end-gate shown in Fig. 3 consists of the top cross-boards S, having hooked 50 ends projecting beyond the outer edges of the upright pieces S', said hooked ends being adapted to engage over the upper edges of the side-boards W.

What I claim is—

A convertible hay-rack, comprising in combination with the bed having longitudinal pieces A and end pieces with recessed ends into which the ends of said side pieces are seated, the wings having bolts secured to the 60 cross-pieces thereof, and designed to engage in apertures C in said pieces A, the standards P and socket-plates secured to the cross-pieces of said bed, said standards having apertures therein, the extensible bars having 65 bracket-straps for supporting the inner ends of said bars, and allowing same to slide longitudinally in contact with each other, the outer ends of said bars adjustably held in said apertured standards, as set forth. 70

In testimony whereof I have signed my name to this specification in the presence of two subscribing witnesses.

DANIEL M. COX.
